LOUIS SCHOTT, OF CINCINNATI, OHIO, ASSIGNOR TO THE CINCINNATI GALVANIZING COMPANY, OF CINCINNATI, OHIO, A CORPORATION OF OHIO

PAINTING DEVICE

Application filed June 11, 1930. Serial No. 460,363.

This invention relates to a method and means for applying a protective and decorative coating to the bottom flange of containers and the like.

5 The object of the invention is to provide means whereby said operation can be performed in an efficient and workmanlike manner in a minimum of time.

Another object is to provide such means 10 which require but a minimum of skill in the use thereof, whereby the expense involved in the employment of skilled manual labor for performing the coating operation is eliminated.

15 Another object is to provide a means of the class described which is simple and inexpensive in construction.

These objects are attained by the means described herein and set forth in the accompanying drawings, in which:

20 Fig. 1 is a side elevational view of the device of this invention, showing a container operatively positioned thereon, parts being shown in cross section.

25 Fig. 2 is a view taken on line 2—2 of Fig. 1.

Fig. 3 is a top plan view of a part of the invention.

30 Fig. 4 is a side elevational view, partly in section, of apparatus for painting container covers or lids.

In the manufacture of metal pails, refuse cans and many other kinds of metal ware of the same character which are normally used 35 somewhat roughly and which are subjected to moisture and the elements it has been found that the known processes of galvanizing or zinc baths effectively protect the body of such ware but the galvanizing on

40 the bottom flange or ridge upon which the articles rest will oftentimes become slightly faulty due generally to the drawing of these hoops or bottom flanges or beads in process of fabrication. The most effective

45 way to prevent rusting of these bottom or wear flanges is to coat them on both sides and the bottom edge with a suitable substance. The use of the ordinary paint brush requires too much time and also a degree of 50 skill if the visible exterior band of paint is

to be uniform and evenly applied and hence is prohibitive in cost. These articles cannot be effectively dipped in paint or coating material because the air pocket which is formed between the recessed bottom, the 55 wear flange and the surface of the paint keeps the liquid paint from rising on the inner circumference of the band.

The present invention provides a method and means whereby these difficulties and high 60 costs are eliminated so that the work of coating or painting both the inner and outer circumference and the edge of the flange is performed rapidly and at one operation.

The type of container is well known and 65 in wide use and comprises a generally cylindrical body which may be corrugated and a bottom, surrounding and reinforcing the container. At the bottom is a hoop like band or flange which depends below the normal 70 bottom wall of the container and upon which the container rests. The flange is of heavier gage metal and withstands most of the abuse and strain to which the container is subjected, the bottom wall being spaced at a distance from the bottom edge of the flange.

The device comprises an inclined frame 75 upon which one or more pairs of support members are mounted. The support members may comprise removable bars with arcuately 80 arranged open journal members which receive the cylindrical body. Adjacent the lower portion of the inclined frame is a standard having a table portion serving as a base rest for holding the container in its inclined position 85 during the painting process. Associated with the standard and table portion is a treadle which simultaneously actuates a brush and a can of paint into contacting relationship 90 with the bottom flange on the container, the paint can being disposed directly beneath the lowermost portion of the angularly-disposed container whereby said portion enters into the liquid to the depth of the bottom flange, the brush being held against the exterior face of the flange while the container is revolved, smoothly spreading the liquid thus applied.

A preferred form of constructing the device of the present invention is set forth herein. A substantially rectangular frame 95 is

provided, comprising a pair of front standards 6 and a pair of rear standards 7. The front and rear standards may be joined by lateral base ties 8, and are further provided with a pair of raised members 9 extending therebetween. Members 9 are joined intermediate their ends by a cross bar 10. Front standards 6 are connected by a lower cross member 11 and an upper cross member 12. A pair of angularly-disposed supports 13 extend, one each, between the top of one of the rear standards 7 and the fore portions of the raised member 9 adjacent thereto. Transverse connectors 14 are positioned in spaced relationship upon supports 13 adjacent the middle thereof. As shown herein, connectors 14 are removably received in aligned slots 15 formed in supports 13. An arcuate arm 16 is secured to the upper 20 surface of each connector 14. Arms 16 may be U-shaped in cross section, whereby said arms may be conveniently secured to connectors 14 by means of screws 17, or the like, passing through the base portions of the arms into the 25 connectors. Arms 16 are set in alignment and are adapted to receive the cylindrical body portion of a container 18.

The operative parts and associated elements of the present invention comprise a 30 treadle 19 pivotally mounted as at 20 upon member 11. The inner end 21 of treadle 20 has pivotally secured thereto, as at 22, a carrier member 23 adapted to support a can 24 of paint or coating liquid, upon its upper 35 surface. Carrier 23 is vertically movable, by means of treadle 19, between a pair of slides 25 suitably secured to frame 5, the carrier being provided with a pair of slide blocks 26. A table member 27 is attached to upper 40 cross member 12 in substantially right angle relationship with supports 13. The attachment of table 27 to cross member 12 is adjustable, consisting of a bolt 28 passing through the inner portion of an elongated 45 slot 29 in the table and through member 12 whereby said table may be adjusted toward and away from the supports 13 and secured in its adjusted position by means of a nut 39. One end of a lever arm 30 is pivotally mounted 50 in the outer end of slot 29, the free end of said arm having a brush 31 pivotally attached thereto. The lower end of table 27 has secured upon its upper surface a lug or disc 32 and a pair of guide brackets 33. A 55 link 34, adjustable as to its length, as indicated at 35, is pivotally connected at one end 36 to arm 30, and at its other end 37 to treadle 19.

The operation of the device is as follows: 60 After a can of paint has been mounted upon carrier 23, a container 18 is positioned within the aligned arms 16. The edge of a portion of base flange 38 of the container rests against the properly adjusted table 27. The flange 65 is guided by the lug 32 contacting its inner

face while drip guides 33 are disposed adjacent its outer surface. The treadle 19 is now actuated downwardly whereupon the can of paint is carried upwardly and the 70 lowermost portion of container 18 is submerged in the coating liquid, to the height of the flange 38, the liquid being maintained at the proper level for this purpose. Simultaneously with the upward movement of can 24, lever arm 30 is actuated downwardly 75 through the medium of link 34, so that brush 31 contacts the opposite outer surface of flange 38 and spreads the coating liquid smoothly thereover as the container is rotated. The inner face of the flange is, of course, covered by the coating liquid in the immersion process, but inasmuch as said face is unexposed and invisible when the container is in use, it is unnecessary that a brush be applied thereto. When the flange has 80 been thoroughly coated the treadle is allowed to rise and another container placed in position. The adjustment of table 27 and the movement of the various parts are sufficient to permit of the work being done upon the 85 standardized sizes of containers commonly in use. The device is obviously operative if the brush 31 is manually held against the flange 38 while the can is revolved.

The covers for pails and containers also 90 have the usual beaded edge painted to preserve them. This may be done with the apparatus shown in Fig. 4 which consists of a table like member 39, suitably inclined and having a thick segmental block 40 which supports the cover for manual rotation with its beaded edge overhanging below the edge of the table into a shallow container of paint. The radius of the block is such as to fit inside 95 of the cover and the block is of a height or thickness sufficient to prevent the bead from scraping the table. By holding a brush at the periphery of the cover the paint stripe is made true and uniform and the covers may be placed upon a suitable rack to drain off 100 any surplus paint which may adhere to the inner edges. Such rack may be made up of blocks on an inclined table substantially like 105 that in Fig. 4. A drip catch container or its 110 equivalent replaces the paint pan.

What is claimed is:

1. A device for applying coating liquid to the base flange of cylindrical containers and the like and comprising an inclined frame with aligned arms for receiving the body portion of a container, a table member for supporting the base of the container, said member being adjustable toward and away from the inclined frame, a treadle pivotally connected to the frame and having a carrier 120 at one end adapted to hold a can of coating liquid, said carrier being adapted upon downward actuation of the treadle to approach the lowermost portion of the container whereby said portion is immersed in 125 liquid.

- the liquid, said treadle being likewise connected by means of a link to a lever arm pivotally secured to said table member and having a brush pivotally attached to its end,
- 5 downward movement of the treadle serving to move the brush into contacting relationship with the outer face of the base flange for spreading thereon the coating liquid upon rotation of the container.
- 10 2. A device for coating the end flanges of cylindrical containers and the like and comprising a frame having adjustable means thereon for supporting a container in an angular position, a treadle pivotally connected to said frame, a carrier for supporting a can of coating liquid, said carrier being pivotally connected with and vertically movable by means of said treadle, and a brush pivotally connected with the treadle, downward move-
- 15 ment of the treadle serving to actuate the carrier upwardly for immersing the lowermost portion of the container in the liquid, said downward movement likewise serving to actuate said brush against the container flange
- 20 for spreading the liquid thereon when the container is rotated on its supporting means.
- 25 3. A device for painting end flanges on cylindrical bodies and the like and comprising a frame having means for supporting a body in an angular position, a treadle connected to said frame, and a paint carrier and brush each pivotally attached to the treadle and adapted upon movement thereof, to approach the cylindrical body whereby one
- 30 portion of the body is immersed in the coating liquid and an opposite portion is contacted by the brush, rotation of the body in its supports resulting in the application and spreading of the coating liquid thereon.
- 35 40 In testimony whereof, I have hereunto subscribed my name this 6th day of June, 1930.
- LOUIS SCHOTT.
